DESIGN FOR AN INNER SOLE

Georgene Averill, New York, N. Y.

Application August 18, 1944, Serial No. 114,933

Term of patent 14 years

(Cl. D7—5)

To all whom it may concern:

Be it known that I, Georgene Averill, a citizen of the United States and a resident of the city of New York (Borough of Manhattan), in the county of New York and State of New York, have invented the new, original, and ornamental Design for an Inner Sole, of which the following is a specification, reference being had to the accompanying drawing, forming part thereof, in which—

Figure 1 is a plan view of an inner sole showing my new design; and

Fig. 2 is a side elevational view thereof.

I claim:

The ornamental design for an inner sole, as shown.

GEORGENE AVERILL.
